FREEZING TRAY

Roy M. Cummins, Akron, Ohio

Application February 20, 1945, Serial No. 578,828

2 Claims. (Cl. 62—108.5)

1

The present invention relates to refrigeration and more particularly to freezing trays for use in the freezing chambers of domestic refrigerators for making ice in the trays.

An important object of the present invention is to provide a freezing tray of this character in which the ice is frozen in cylindrical form whereby to facilitate its use in vacuum bottles.

It is also an object of the invention to construct the freezing tray of a form adapted for freezing the ice in cube form, or in any other desired shape.

A further object of the invention is to provide a freezing tray of this character embodying a plurality of spaced apart tubular members in which the ice is frozen together with means for detachably mounting the tubular members in liquid tight engagement with a bottom plate whereby to facilitate the removal of the ice from the tray.

A further object of the invention is to provide a device of this character of simple and practical construction, which is efficient and reliable in use, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which—

Figure 1 is a top plan view,

Figure 2 is a side elevational view,

Figure 3 is an end elevational view,

Figure 4 is an enlarged fragmentary sectional view taken substantially on a line 4—4 of Figure 1,

Figure 5 is an enlarged fragmentary sectional view of the lower end of the center clamping bolt,

Figure 6 is a fragmentary top plan view of a modified tray construction,

Figure 7 is a fragmentary side elevational view thereof,

Figure 8 is a fragmentary side elevational view showing the ice forming tube removed from the bottom clamping plate, and

Figure 9 is a fragmentary sectional view taken substantially on a line 9—9 of Figure 2.

Referring now to the drawing in detail wherein for the purpose of illustration I have disclosed a preferred embodiment of the invention, the numeral 5 designates a bottom clamping plate of elongated construction and formed in its upper surface with a plurality of annular recesses 6.

The recesses 6 are adapted to loosely receive

the lower ends of tubular members 7 extending downwardly in spaced apart relation from an upper clamping plate 8 having openings 9 therein in alignment with the tube to provide an open upper end therefor.

A gasket 10 or rubber or other suitable material is placed in the recesses 6 in engagement with the lower end of the tube to provide a liquid tight seal at the lower ends of the tubes.

10 The clamping plates 5 and 8 as well as the tubes 7 may be constructed of any suitable material and where such parts are constructed of molded or fibrous material a metallic sleeve may be embedded in the lower clamping plate 5 in which the lower end of a bolt 12 is threadedly engaged, the upper end of the bolt extending upwardly through the upper clamping plate 8 and secured thereto by means of a wing nut 13 of substantially flat construction and provided with a relatively 15 thick central portion 14 countersunk in the top of the upper clamping plate 8, as shown to advantage in Figure 9 of the drawing. To the ends of the lower clamping plate 5 are pivotally attached the lower ends of clamping bolts 15 adapted for swinging outwardly at the ends of the 20 tray and providing slots 16 at the ends of the upper clamping plate 8 for receiving the upper portions of the bolts in clamping engagement therewith by wing nuts 17 threaded on the upper 25 ends of the bolts 15.

The tubes 7 may be constructed of cylindrical formation as illustrated in Figures 1 to 4 inclusive, or the tubes may be of square shape in cross section as illustrated at 18 in Figure 6 of the drawing 30 and adapted to have their lower ends inserted in complementary-shaped recesses in the lower clamping plate.

By clamping the upper clamping plate 8 and lower ends of the tubes 7 in recesses in the lower clamping plate a liquid-tight seal will be provided therefor whereby to prevent the escape of water when placed in the tubes.

After the water has become frozen the tubes 7 may be removed by releasing the bolts 12 and 15 and lifting the tubes and upper clamping plate 8 upwardly in the manner as illustrated in Figure 8 of the drawing.

In view of the foregoing description taken in conjunction with the accompanying drawing it is believed that a clear understanding of the construction, manner of use and advantages of the device will be quite apparent to those skilled in the art. A more detailed description thereof is accordingly deemed unnecessary.

It is to be understood however, that even though

I have herein shown and described a preferred embodiment of my invention, that the same is susceptible to certain changes fully comprehended by the spirit of the invention as herein described, and the scope of the appended claims.

Having thus described the invention, what I claim is:

1. A freezing tray for refrigerators comprising upper and lower elongated plates, said upper plate having a plurality of openings, tubes formed on the under side of the upper plate beneath the openings, said lower plate having a plurality of recesses adapted to receive the lower ends of the

tubes for closing said lower ends, and bolts securing the plates to each other.

2. A freezing tray for refrigerators comprising upper and lower elongated plates, said upper plates having a plurality of openings, tubes formed on the under side of the upper plate beneath the openings, said lower plate having a plurality of recesses adapted to receive the lower ends of the tubes for closing said lower ends, and bolts securing the ends and an intermediate portion of the plates to each other.

ROY M. CUMMINS.
